UNITED STATES PATENT OFFICE.

HERMAN ANSHER AND BRUNO F. SPRANGER, OF AURORA, ILLINOIS.

LATCH.

SPECIFICATION forming part of Letters Patent No. 394,949, dated December 25, 1888.

Application filed July 6, 1888. Serial No. 279,159. (No model.)

To all whom it may concern:

Be it known that we, HERMAN ANSHER and BRUNO F. SPRANGER, citizens of the United States, residing at Aurora, in the county of 5 Kane and State of Illinois, have invented a new and useful Improvement in Latches for Doors, of which the following is a specification.

The invention relates to improvements in 10 latches for doors, having for its object to provide a simple device whereby the door, although held closed against the force of the wind and accidental jars, may be opened by a mere pressure, without the inconvenience of 15 turning a knob or lifting a latch; and it consists in a certain novel construction and combination of devices, fully set forth hereinafter in connection with the accompanying drawings, wherein—

20 Figure 1 is a perspective view of a door provided with the improved latch. Fig. 2 is a side view of the latch with part of the casing removed. Fig. 3 is a vertical transverse sectional view on the line *x x* of Fig. 3. Fig. 4 25 is a detail view of the socket-plate.

Referring by letter to the drawings, A designates the face-plate of the latch, which is provided at its center with a rectangular opening, C; and B designates a case, which is attached to the rear side of the said plate over 30 the opening therein.

D represents a follower, which is mounted in the case, and is provided with the forwardly-projecting arms E E, between which is 35 mounted the roller F, the outer side of which projects through the opening C in the face-plate. The follower is further provided on its rear side with the stem G, on which is coiled the spring H, which bears at its front end 40 against the follower, thereby normally holding the latter extended forward with the outer side of the roller projected beyond the face-plate.

I represents a lever, which is provided with 45 lateral trunnions *i i*, mounted in vertical slots J J in the sides of the case, whereby the lever may be moved vertically, and the lower end of the lever is provided with the detent K, which is adapted to engage in either of the 50 notches *k k'*. The rear end of the spring H bears against the lever below the trunnions

i i, whereby the detent K is normally held in engagement with one of the said notches.

L represents an aperture in the lever, which is aligned with the stem G on the follower 55 when the detent K is engaged in the upper notch, *k*; but when the detent is engaged in the lower notch the rear end of the stem abuts against the lever and cannot be repressed.

60 A key-hole, M, is formed in the side of the lock-case near the upper end of the lever, and when the key is inserted and turned it is adapted to engage the said upper end of the lever, and after repressing it sufficiently to 65 disengage the detent K either raise or lower it, according to whether it is desired to open the lock or secure it against being opened.

The latch N comprises the striking-plate O, which is secured to the casing of the door, 70 and the socket or depression P at the center of the said plate, which is adapted to receive the projecting side of the roller F, and therefore it will be seen that when the door is closed the roller will strike the plate O, and thereby re- 75 press the follower against the strength of the spring H, and when the roller aligns with the socket or depression P it will be forced out by the said spring and engaged therewith. A door provided with the improved latch re- 80 quires no knob or latch, and is preferably provided on each side with a simple loop-handle, Q, which may be attached in any suitable manner.

85 It will be seen that the latch is simple, and cannot therefore be readily damaged or put out of order, and the operation of the door to which it is attached is simple, as it requires no manipulation of a knob or similar device. During the day the lever in the latch is al- 90 lowed to remain in alignment with the stem of the follower, whereby the roller may be repressed by pressing upon the door, and at night when it is desired to secure the door against being opened the lever is lowered by 95 means of the key to the locked position de- scribed hereinbefore, when the follower can- not be repressed.

The spring described herein, which oper- 100 ates the follower, may be made of any desired strength, and is preferably sufficiently strong to require a considerable pressure on the door

to open it, so that the wind or an accidental jar or pressure will not disengage the latch.

Having thus described the invention, we claim—

- 5 1. In a latch, the combination of the follower provided with a roller on its outer side and a stem, G, on its inner side, the longitudinally-movable lever provided with an aperture adapted to be aligned with the said stem, 10 and the spring coiled on the stem and bearing at its ends, respectively, against the rear side of the follower and the lever, substantially as specified.
- 15 2. In a latch, the combination, with the follower provided with the stem G, of the lever provided with lateral trunnions mounted in slots J J in the case, and having a detent, K, to engage suitable notches, k k', the lever being further provided with an opening, L, to register with the rear end of the stem G when the 20 detent K is engaged with the notch k, and the spring arranged on the stem and bearing on the lever between its pivot and the detent K, whereby the detent is normally held in engagement with one of the notches, substantially as specified.
- 25 3. The herein-described latch, comprising

the case B, the follower mounted in the case and provided with the stem G and the forwardly-projecting arms E E, the roller 30 mounted between the said arms, the lever I, having the aperture L to receive the rear end of the stem G, and provided with the lateral trunnions i i, mounted in longitudinal slots J J in the sides of the case, the detent K on 35 the lower end of the lever, adapted to engage notches k k' in the case, the said case being provided with a key-hole, M, to enable a key to be inserted to repress the upper end of the lever to disengage the detent from the 40 notches, and the spring coiled on the stem G and bearing against the rear side of the follower and the lower arm of the lever I, whereby the detent K is normally held in engagement with one of the notches k k', substantially as and for the purpose specified. 45

In testimony that we claim the foregoing as our own we have hereto affixed our signatures in presence of two witnesses.

HERMAN ANSIER.
BRUNO F. SPRANGER.
